US00D522438S

(12) **United States Design Patent** (10) **Patent No.:** **US D522,438 S**
Kern (45) **Date of Patent:** **** Jun. 6, 2006**

(54) **WHEEL**

(75) Inventor: **Steven J. Kern**, Playa del Rey, CA
(US)

(73) Assignee: **GB Automotive Products, Inc.**,
Hawthorne, CA (US)

(**) Term: **14 Years**

(21) Appl. No.: **29/241,393**

(22) Filed: **Oct. 27, 2005**

(51) **LOC (8) Cl.** **12-16**

(52) **U.S. Cl.** **D12/209**

(58) **Field of Classification Search** D12/204-213;
301/37.101, 64.101, 65

See application file for complete search history.
